Application November 28, 1947, Serial No. 152,842

Term of patent 3½ years

(Cl. D45—4)

To all whom it may concern:

Be it known that I, Herman Bogoff, a citizen of the United States, residing at Chicago, in the county of Cook and State of Illinois, have invented a new, original, and ornamental Design for a Link Bracelet, of which the following is a specification, reference being had to the accompanying drawing, forming part thereof, wherein—

Fig. 1 is a plan view of a link bracelet, showing my new design; and

Fig. 2 is a side elevation thereof.

The links outlined in dot and dash lines are

duplicates of those shown in full lines. The dominant features of my design reside in the link elements shown in full lines, the two left hand elements being repeated alternately throughout the length of the bracelet as illustrated by the broken lines.

I claim:

The ornamental design for a link bracelet, as shown and described.

HERMAN BOGOFF.
